CLAIM

The ornamental design for a display panel portion with an animated computer icon, substantially as shown and described.

DESCRIPTION

FIG. 1 is a first image in a sequence for a display panel portion with an animated computer icon, showing our new design;

FIG. 2 is a second image in the sequence;

FIG. 3 is a third image in the sequence;

FIG. 4 is a fourth image in the sequence;

FIG. 5 is a fifth image in the sequence;

FIG. 6 is a sixth image in the sequence;

FIG. 7 is a seventh image in the sequence;

FIG. 8 is an eighth image in the sequence;

FIG. 9 is a ninth image in the sequence;

FIG. 10 is a tenth image in the sequence;

FIG. 11 is an eleventh image in the sequence; and,

FIG. 12 is a twelfth image in the sequence.

The appearance transitions sequentially from FIG. 1 through FIG. 12. The process or period in which an image transitions to another form no part of the claimed design.

The outermost broken line rectangle shows the display panel portion and forms no part of the claimed design. The remaining broken lines show portions of the computer icon and form no part of the claimed design.
